UNITED STATES PATENT OFFICE.

GEORGE A. MCILHENNY AND THOMAS G. LANSDEN, OF WASHINGTON,
DISTRICT OF COLUMBIA.

HYDRAULIC MAIN FOR GAS-WORKS.

SPECIFICATION forming part of Letters Patent No. 380,911, dated April 10, 1888.

Application filed April 11, 1887. Serial No. 234,401. (No model.)

To all whom it may concern:

Be it known that we, GEORGE A. MCILHENNY and THOMAS G. LANSDEN, both of the city of Washington, in the District of Columbia, have invented certain new and useful Improvements in Hydraulic Mains for Gas-Works; and we do hereby declare that the following specification, taken in connection with the drawings furnished and forming a part of the same, is a clear, true, and complete description of our invention.

Our said improvements relate to the dip-pipes within the hydraulic mains, and to means for providing a direct communication between the interior of a dip-pipe and the interior of the main above the usual water-seal. Various means have heretofore been devised for this purpose; and the prime object of our present invention is to provide an economical, simple, effective, and easily-operated valve mechanism which will enable a prompt and perfect closure at the valve-seat without that liability of derangement heretofore known to exist because of the inevitable presence of obstructive matter.

Various forms of sliding gates have heretofore been employed—as, for instance, as disclosed in the Letters Patent No. 247,386, issued to George A. McIlhenny September 20, 1881, and we have also used a tapered plug-valve, as disclosed in said McIlhenny's Letters Patent No. 282,345, July 31, 1883; but, while each of said prior improvements possessed practical value as compared with means used prior thereto, there were certain objections encountered in their practical operation, which we have now sought to overcome. In the use of the sliding gate or valve the irregular accumulations of solid matter on the coincident surfaces at times rendered the closure more or less unreliable, and while the aforesaid tapered plug-valve as heretofore used effectually obviated that difficulty, it was so organized as to essentially require a horizontal valve-stem projecting through the side of the hydraulic main and essentially involved the use of packing-glands and a consequent lack of freedom in the movement of the valve.

The advantages incident to a vertically-operated valve-stem have heretofore been partially attained by providing valve-chambers

outside of and above the hydraulic main, either as a part of a specially-formed length of a vertical outside section of dip-pipe or as a separate structure, coupled by a lateral pipe to the dip-pipe above the main, and with the side of the main by a vertical elbow, and with such outside chambers weighted cup-valves of different forms have been employed.

We have now provided the dip-pipe within the main with a lateral connecting-chamber having a circular hole in its top to serve as a valve seat, and we employ therewith a conical valve provided with a vertical stem housed within a vertical pipe-seal of a well-known form on top of the main, thus securing a reliable gas-tight joint, perfect freedom of movement by the valve and its stem, and, if desired, a capacity to close by its own gravity and yet secure a gas-tight joint at its seat, regardless of ordinary obstructive matter thereon, all at very low cost and with a minimum expense for repairs and adjustment; and one very important feature is, that our improvements can be readily and cheaply applied to dip-pipes and mains already in use.

After fully describing our invention in connection with the drawings, the features deemed novel will be specified in the several clauses of claim hereunto annexed.

Figure 1 is a view of the outer end of a retort, an ascension-pipe coupled at its top to a dip-pipe, and a hydraulic main in cross-section having our improvements applied thereto. Fig. 2 is an enlarged sectional view of a portion of said main, the lower end of the dip-pipe, its valve-chamber, and the valve in accordance with our invention. Fig. 3 is a lateral section of said dip-pipe and the valve-chamber on line x, Fig. 2. Fig. 4 is a lateral section illustrating the hydraulic main, an ascension-pipe terminating within a pendent dip-pipe, and provided with our present improvements.

In Fig. 1 the retort A, ascension-pipe B, dip-pipe C, and hydraulic main D are clearly indicated, the ejection end a of the dip-pipe being water-sealed in the usual manner.

At one side of the dip-pipe, at its end a, is the valve-chamber E, which is essentially heated within the hydraulic main and is in open communication with the interior of the dip-

pipe. This valve-chamber may have a bottom; but it is preferably without one, as shown, its vertical walls dipping into the water in the main, like the end of the dip-pipe. The location of this valve-chamber and valve within the hydraulic main enables ordinary dip-pipe elbows to be used above the main with attendant economy in space as well as in cost of construction, and it also obviates many pipe-joints with incident leakage, more or less liable to the use of valve-chambers located outside of said main.

The top *b* of the valve-chamber is horizontal and provided with a circular hole, *b'*, the edges of which serve as a valve-seat, and said edges should be sharp enough to enable them to cut through obstructive matter interposed between the seat and the valve-plug *F* when the latter is dropped for closure. The valve or valve-plug *F* is tapered, and with its stem *c* should be heavy enough to ordinarily effect a closure by its own weight.

In the top of the main, centrally over the valve-seat *b'*, a tapped hole receives the vertical pipe *d*, within which the valve-stem *c* is guided, although loosely fitted, so as to secure absolute freedom of vertical movement. Surrounding said pipe *d* is the large pipe *e*, closed at its bottom and open at its top, for the reception of water within the annular space around the pipe *d*. The valve-stem *c* has pendent from its upper end the pipe *f*, which is closed at its top, open at its bottom, surrounds the pipe *d*, and occupies said annular space, which, when filled with water, affords a water-seal in a manner well known and as variously used in other connections.

The top of the valve-stem is coupled to a lever, *g*, provided with a pendent hand-rod, *g'*, accessible at the front of the retort-bench.

It will be readily seen that the dip-pipe may have the valve-chamber *E* formed integrally therewith, as when newly constructed; or they may be separately made and bolted together, as when the chamber is to be applied to dip-pipes already in use, the latter only requiring a series of lateral holes for gas-ducts, or an opening cut away therein in lieu thereof, and that in either event the cost will be trifling. It will also be seen that a single tapped hole in the top of the main is required for mounting the valve in position, and that the mere dropping of the valve will insure good closure. If at any time the valve-seat or the plug should

become unduly clogged with solid matter, rendering a clearing effect desirable, it will be only necessary to detach the valve-stem from its lever, and by the rotation of the stem and the churning of the valve on its seat to secure a perfect closure.

In Fig. 4 another arrangement is shown, in which the ascension-pipe *B'* terminates in a detachable pendent dip-pipe, *C'*, which is provided with a lateral valve-chamber, *E'*. The aperture in the top of the main *D'* conforms to the lateral outline of the dip-pipe and chamber, and the flange *h*, which supports them, has a corresponding form, and the valve-stem seal is mounted in said flange, thus providing a dip-pipe and valve all complete and ready for attachment to a main of this type, and requiring only that the top of the main should be cut away at one point to admit of the introduction of a dip-pipe having the lateral valve-chamber.

While the best results will accrue from the use of the valve-chamber, the conical valve, and the vertical valve stem freely carried within the water-sealed pipe, as shown, the economic and effective advantages of the dip pipe provided with the lateral valve-chamber, the conical valve, and the vertical valve-spindle will accrue even if the latter be provided with other well-known forms of packing and sealing contrivances.

Having thus described our invention, we claim as new and desire to secure by Letters Patent—

1. The combination, with a hydraulic main, of a dip-pipe provided with a lateral valve-chamber located within said main, a valve-seat in the top of said chamber, and a conical valve provided with a vertical stem projecting through the top of the main, substantially as described.

2. The combination, with a hydraulic main, of a dip-pipe provided with a lateral valve-chamber located within said main, a valve-seat in the top of said chamber, a conical valve provided with a vertical stem, and a water-sealed pipe serving as a guide for said stem, substantially as described.

GEORGE A. McILHENNY.
THOMAS G. LANSDEN.
